UNITED STATES PATENT OFFICE.

JOHN PRENTICE, OF BAYONNE, NEW JERSEY, ASSIGNOR TO THE BABCOCK & WILCOX COMPANY, OF BAYONNE, NEW JERSEY, A CORPORATION OF NEW JERSEY.

BAFFLE FOR BOILERS.

Application filed February 15, 1922. Serial No. 536,696.

To all whom it may concern:

Be it known that I, JOHN PRENTICE, a citizen of the United States, residing at Bayonne, in the county of Hudson and State 5 of New Jersey, have invented certain new and useful Improvements in Baffles for Boilers, of which the following is a specification.

My present invention relates to baffles arranged to extend across the water tubes of 10 boilers, particularly where such tubes are horizontal and arranged in horizontal rows. It will be understood that in the term "horizontal", I also include tubes which are horizontally inclined, as is the usual practice. 15 My invention also particularly relates to inclined cross baffles in which the baffle is made up of bricks or tile.

My invention will be understood from the following description and the drawings, in 20 which Figure 1 is a sectional elevation of a well-known type of water-tube boiler, having horizontally inclined water tubes and a cross baffle, illustrating one form of my invention; Fig. 2 is an enlarged section of a portion of the cross baffle shown in Fig. 1; Fig. 3 is a view of Fig. 2 looking from the right of Fig. 2 along the tubes; Fig. 4 is an 25 enlargement of a baffle similar to the inclined baffle shown in Fig. 1 showing a modification; Fig. 5 is a view of Fig. 4 looking from the right of Fig. 4 along the tubes, with the tiles removed; Figs. 6, 7 and 8 are 30 respectively cross section, elevation and plan of the form of backing plate section shown in Fig. 4; Fig. 9 shows another embodiment of my invention as applied to a boiler of the type shown in Fig. 1; Figs. 10 and 11 are 35 enlarged views of a portion of the inclined baffle shown in Fig. 9, Fig. 10 being a section of the lower part of such baffle, and Fig. 11 a view from the right of Fig. 10 looking along the tubes; Figs. 12 and 13 are 40 respectively side and end views of a portion of the tubes showing in more or less 45 diagrammatic form the illustrated embodiment of the form of tile which I use; Fig. 14 is similar to Fig. 12 showing a tile making a less angle with the tubes than does the tile in Fig. 12; Fig. 15 is a side elevation of my 50 illustrative form of tile; Fig. 16 is a view of such tile looking from the left of Fig. 15; Figs. 17 and 18 are respectively section and 55 end views on a larger scale, the section of Fig. 17 being taken on the line 17-17 of

Fig. 18; and Figs. 19 and 20 are diagrammatic views illustrating the method of inserting the sections of the backing plate and the building up of a tile wall in front thereof.

Corresponding reference characters refer to corresponding parts in the several views.

Referring now to the arrangement shown in Fig. 1, the boiler illustrated has the usual headers 10 and 11 and a steam drum 12, the water tubes 13 extending between the headers and being horizontally inclined. The form of boiler illustrated is of the so-called "drop-leg" construction; that is to say, the tubes are divided into banks separated by a 60 space with a plurality of rows of tubes in the lower bank, but the number of horizontal rows in the lower bank being much less in number than the horizontal rows in the upper bank. The boiler is provided 65 with a baffle 14 extending along the lower tubes toward the center of the boiler and from the inner end of the baffle 14 extending upwardly is an inclined baffle which I have 70 designated, generally, by the character 15. 75 This cross baffle 15 is not only inclined to the tubes themselves, but is inclined to the vertical, so that, unless such tendency is overcome, it would fall forwardly or to the right of Fig. 1. The pass across the tubes 80 defined by the headers 11 and the inclined baffle 15 is a constantly decreasing one, and the gases after passing across the tubes may flow over a superheater, as illustrated, and then downward at the left of the baffle 15 85 and between it and a vertical baffle 16. The gases then flow upward between the headers 90 10 and the baffle 16 to the gas outlet.

Because the hottest gases pass through 95 the first pass between the baffle 15 and the headers 11, it is desirable that the face of the baffle 15 adjacent this pass shall be made of some heat resisting material, and I use tile or brick for this purpose. For some purposes, it is desirable to provide a so-called 100 backing plate for the tile wall or walls of the baffle, and this plate may be of cast iron. It will also be understood that not only must the baffle be one which will resist, so far as possible, the action of the heat, but it should be capable of being put in position without undue labor after the boiler 105 has been erected, and furthermore, it should be of such a character that any portion of it may be removed or replaced after the boiler 110

has been in operation. The arrangement which I have provided accomplishes all of these purposes.

In the arrangement shown in Figs. 1 to 8, 5 inclusive, a backing plate made up preferably of cast iron or other metallic sections is built up across the tubes at the angle which it is desired that the baffle shall make with the tubes. The greater portion of the 10 backing plate is made up of sections 17 having recesses 18 along the top and bottom edges of the section, which recesses are arranged to fit around the tubes. The sections are also provided, in the form illustrated, 15 with recesses or interlocking offsets at the top and bottom, as at 19, 20, and the section 17 is designed so that when placed in position, as best shown in Fig. 4, each of the recesses 18 will fit snugly around the tube. 20 The length of the section may be as great as desired, but preferably in a boiler of ordinary width, there will be a plurality of sections placed end to end to cover the entire width of a horizontal aisle in the 25 boiler.

As shown in Fig. 5, the tubes, in the illustrative boiler, are arranged in staggered relation so as to form horizontal and diagonal aisles.

30 Where there is a greater distance between adjacent horizontal rows, the sections 17 are made correspondingly wider, as will be obvious. Such a plate is shown at 21 where a horizontal row of tubes has been omitted.

35 As will be seen from an inspection of Fig. 4, the recesses 19 and 20 are interlocked so that if any section 17 should tend to rotate to the right of Fig. 4, as it would be 40 pulled by gravity, such rotation would be resisted by the contact of its lower edge with the upper edge of the next lower section 17 and by the contact of its upper edge 19 with the lower edge of the next higher section. 45 In other words, no section 17 can fall forward, so long as the lowermost or the uppermost section is held against rotation. As shown in Figs. 2 and 4, the lowermost plate, which extends across the space between the upper and lower banks of tubes, is anchored 50 or backed up to prevent its falling forward.

In the form shown in Fig. 2, the plate 22 has a foot at an angle to the main body of the plate 22, which foot is contacted by a portion of the horizontal baffle 14. In 55 the arrangement shown in Fig. 4, each plate 23 is connected to a strap 24 attached to one of the tubes. If desired, the turning of the individual sections may be prevented by anchoring the top section instead of the bottom section.

60 The backing plate made up of the interlocked plates, such as 17 and 21, is held in position longitudinally of the water tubes by backing bars 25. These bars extend through the diagonal aisles of the tubes and

are held against movement longitudinally of the tubes by clamps 27 attached to the tubes. Each section 17 is contacted by at least one of the bars and, as illustrated, each section rests against at least two of the 70 bars for greater stability. The wide sections, such as 21, may be contacted by cross bars 26 extending through slots in the ends of the bars 25 to hold the plates 21 more certainly against motion longitudinally of the tubes. 75

In the form illustrated, the tile or brick walls in front of the backing plate and constituting the remainder of the baffle, are 80 shown as two in number, though it will be understood that any number of such walls may be used, as desired.

Each wall is made up of a plurality of tiles 28 set edge to edge, each tile being 85 preferably of the form illustrated best in Figs. 15 and 16, and being substantially quadrilateral in elevation with a tube recess at each angle of the quadrilateral. These tile are arranged so that, when in position as shown in Fig. 15, preferably the entire 90 width of the tile will contact with each tube throughout the entire extent of the tube recess. Since usually the baffle will make an angle with the tubes, the side walls of the tile will necessarily make a corresponding 95 angle with the face of the tile. The tiles are arranged to be inserted so as to occupy the position shown best in Fig. 13, with two of the edges of the quadrilateral horizontal and the two remaining edges substantially 100 parallel to the diagonal aisle. As will be seen in Fig. 13, the edges of each tile are contacted by edges of adjacent tiles for the full thickness of the tile and, by reason of the snug fit of the tile around the tubes, a single wall will provide a comparatively 105 tight baffle, and yet one which can be mounted or demounted from position after the boiler has been erected.

110 The tiles illustrated are constructed in such a way that, after they are in position, there will be no tendency for the individual tile to topple forward or to the right of Fig. 12, the direction in which the inclination of the baffle would apparently cause such tile to fall. I accomplish this result by designing each tile so that as it rests in the position shown, for instance, in Fig. 12, a vertical line dropped from the center of gravity will pass to the left of the line of contact between the tile and the tubes on which it rests. Consequently, the tendency for the tile is to rotate counterclockwise in Fig. 12, and thus hold the tube recesses of the tile snugly against the tubes. The same 115 description applies to Fig. 14, in which the tile is shown at a less angle to the tubes than in Fig. 12. It will be obvious by a comparison of Figs. 12 and 14 that the thickness 120 of the tile may be less in the inclination 125 of the tile.

shown in Fig. 14 than in the inclination shown in Fig. 12. In other words, in Fig. 14, the tile may be thinned until its front edge reaches the intersection of the vertical line from the center of gravity with the top of the tubes, and yet the tile will have no tendency to fall to the right of Fig. 14. On the other hand, if a greater inclination to the tubes than that shown in Fig. 12 is desired, it will be obvious that the tiles will have to be thickened accordingly, in order to maintain their individual stability, if gravity alone is to be utilized to hold the tile in place. By a proper coordination of the thickness of the tile and the desired angle of the inclination of the baffle, I am enabled to provide a tile which will contact for its entire width with the tubes and yet may be readily inserted in place. This is illustrated best in Fig. 15, where the tile has been rotated into position by turning on the axis X extending through the line of support between the tile and the tubes on which it rests. It will be obvious that all points of contact between the upper tube to the right of a vertical line from the point X will move away from that tube when the tile is turned counterclockwise. In the form shown in Fig. 15, a very small portion of the tile is shown at the right of such vertical line from the point X, but it will be obvious that such portion is so near the vertical line that substantially all of such points would also move along the tube 15 and then away therefrom. Therefore, such a tile may be rotated into position practically without springing the tubes. While, preferably, I arrange the tiles so that they contact with the tubes for their full width, it will be understood that for some purposes this feature may be modified by arranging the tile so that a portion of each edge must be cut away to permit the tile to be turned into place, thereby reducing the contacting portion between the tile and the tube.

In the form illustrated, the tiles are prevented from falling by contact with the backing plate. This is best shown in Fig. 17. Since the normal from the point on which the tile must turn is shorter than the line of contact of the tile with the tube, any turning of the tile from the full line to the dotted line position of Fig. 17 will result in a bodily motion along the tube which, of course, will be resisted by the friction between the tile and the tube and also when the tubes are inclined to the horizontal, by gravity, since such motion would result in a shifting of the tile bodily upward along the tube.

In order to make a tight baffle, I preferably provide at least two walls of tile. As illustrated in Fig. 13, the wall next to the backing plate is made up of tile in which the long diagonal is inclined to the left of

that figure. The front wall, on the other hand, is made up of tile in which the diagonal extends to the right in Fig. 13, and the tiles in the front wall are arranged in relation to the tiles in the rear wall in such a way that the joint between the sides of the tiles in the rear wall lie behind the solid portion of the corresponding tiles in the front wall. Similarly, the joints between the sides of the tiles in the front wall lie opposite the solid portion of the tiles in the rear wall. This arrangement breaks the joints between the sides of the tile. Similarly, in the form illustrated in Figs. 10, 11 and 13, the upper horizontal edge of each tile in the front wall is higher than the upper edge of the corresponding tile in the rear wall, and similarly, the lower edge of each tile in the front wall is higher than the lower edge of the corresponding tile in the rear wall. This arrangement breaks the joints between the top and bottom edges of the tile. Consequently, with two walls of tile, the joints between the tile are broken so that a relatively tight baffle is provided by the tile alone, and this tightness is reinforced by the backing plate because of the overlapping of the edges of the sections thereof, which are also arranged so that the joints therein do not come opposite any of the joints in the rear wall of the tile. Since the two walls of tile are in contact with each other and the rear wall of tile is in contact with the backing plate, any tendency of each tile to fall forwardly in the direction of the inclination of the baffle is prevented by the fact that a portion of each tile extends below the line of contact between the front face of the tile and the tubes on which it rests. Consequently, if the tile is tilted clockwise, as illustrated in Fig. 17 by dotted lines, the part below the line of support will resist such turning, by reason of its contact either with the other wall of tile or with the backing plate, as the case may be. In other words, in order to turn the tile 28 from the position shown in Fig. 17 in full lines, it will be necessary to move the tile bodily along the tubes, and when the tubes are inclined to the horizontal, as illustrated, such a motion would be resisted by gravity which tends to cause the tile to slide down the tubes to remain in contact with the backing plate or the other wall of tile.

One of the advantages of the arrangement which I have illustrated resides in the fact that, because of the horizontal inclination of the tubes, all parts of the baffle tend to slide down the tubes, and therefore to hold the several parts together in the position shown in the several figures, and thus hold the several parts in such position that no one of them will fall out of place. By reason of the attachment of the backing bars to the tubes, the baffle is held in the desired

position against this tendency to slide down the tubes.

In Figs. 19 and 20, I have illustrated a method by which the baffle may be built in place. The backing bars 25 are first placed in position and attached to the tubes by the clamps 27. Then the backing plate is built up section by section beginning at the bottom, each section being inserted lengthwise down a diagonal line, as shown in Figs. 19 and 20 at 171. Then the section is turned endwise into the position indicated at 172, and then the section is rotated on its long axis into the position 173. Now the section is again turned flatwise into the position shown at 174, from which position it may be turned through the position 175 until the recesses are in contact with the tubes, and the section is then slid into position 20 against the backing bars 25. Similarly, the tile walls are built up beginning at the bottom, each tile being passed flatwise through a diagonal aisle and then turned until it lies in a position shown in dotted lines at 281 of Fig. 17, from which it may be rotated into its position against the backing plate.

In the tube arrangement shown in Fig. 13, it will be seen that the tubes in the horizontal rows are staggered in such a manner that a straight diagonal line cannot be drawn through all of the tubes. For this reason, each wall will have two shapes of tile, differing slightly to take care of this particular arrangement. If, as is sometimes the case, the tube arrangement were such that a diagonal line could be passed through the centers of all of the tubes along a diagonal aisle, then each wall would have one form of tile only.

Because the lower bank in a drop-leg construction usually has a comparatively small number of horizontal rows of tubes, it is desirable to support the baffle in such a way that the weight is carried by the large number of rows in the upper bank. To this end, I provide means by which the tile forming part of the baffle which extends across the space in the drop-leg construction shall be supported on the backing plate, and so that the part of the backing plate extending across this space shall be suspended from the upper bank of tubes. In the form illustrated in Figs. 4 and 5, the plate 23 is suspended from the clamps 24, each of which surrounds one of the tubes in the upper bank. The plate 23 has pins 29 attached thereon and located on centers corresponding to the centers of the tubes. On each of the pins 29 may be supported a round piece 30 of the same diameter as the tube, this piece 30 may be either of refractory material or of metal. It will be obvious, therefore, that the tile walls extending across the space between the two banks of tubes can be built up precisely the same as on the tubes

themselves, the same shapes and sizes of tile being used and the weight of such tile will be carried through the pins 29 to the plate 23, and from there to the tubes of the upper bank.

Instead of the arrangement of dummy tube centers shown in Fig. 4, I may provide the arrangement shown in Figs. 10 and 11, in which metallic or refractory pieces 31 of the same diameter as the tubes and arranged on similar centers, are held to the backing plate 32 by bolts 33, the tile being mounted on these dummy portions of tubes similar to the way in which the tiles are mounted on the tubes themselves. In this arrangement, the plate 32 is not suspended from the upper tubes, but obviously provision to that end may be made, if desired, in any suitable manner, as for instance, that illustrated in Fig. 4. For instance, the system of backing bars may be supported from the top of the backing plate as by a hook 34 (Fig. 4) and the plate 32 may be connected to the system as shown in Fig. 10. Because of the cross bars 26 extending through slots in the bars 25, the entire weight of the backing bar system and anything attached thereto will be carried on the backing plate and thus distributed over the entire upper bank of tubes 13.

While I have shown my baffle in its preferred form, it will be understood that many of the details may be varied within wide limits. It will also be obvious that certain features of my invention may be used alone or in combination with other arrangements. It will also be obvious that, while the baffle which I have described is particularly adapted for inclined cross baffles, many of its features will be useful in vertical baffles, particularly where the horizontal tubes are inclined.

I claim:—

1. An inclined cross baffle for water-tube boilers having horizontally inclined tubes arranged to form horizontal and diagonal aisles, having tiles each substantially quadrilateral in elevation and having a recess at each angle of the quadrilateral, each recess being adapted to fit snugly around a tube the entire thickness of the tile, with two of the sides quadrilateral horizontal and the two remaining sides substantially parallel to a diagonal aisle.

2. An inclined cross baffle for water-tube boilers having horizontally inclined tubes arranged to form horizontal and diagonal aisles, having tiles each substantially quadrilateral in elevation and having a recess at each angle of the quadrilateral, each recess being adapted to fit around a tube with two of the sides of the quadrilateral horizontal and the two remaining sides substantially parallel to a diagonal aisle, with the center of mass of the tile in the rear of the line of

contact of the front face of the tile with the two tubes on which it is supported.

3. An inclined cross baffle for water-tube boilers having horizontally inclined tubes arranged to form horizontal and diagonal aisles, having tiles each substantially quadrilateral in elevation and having a recess at each angle of the quadrilateral, each recess being adapted to fit snugly around a tube the entire thickness of the tile, with two of the sides of the quadrilateral horizontal and the two remaining sides substantially parallel to a diagonal aisle, said tile being constructed and arranged so that, on being turned from its normal position on the line of contact of its front face with the two tubes on which it is supported, all parts of the tile recesses will move away from the parts of the tubes with which they are in contact when in normal position.

4. An inclined cross baffle for water-tube boilers having horizontally inclined tubes arranged to form horizontal and diagonal aisles, having tiles each substantially quadrilateral in elevation and having a recess at each angle of the quadrilateral, each recess being adapted to fit snugly around a tube the entire thickness of the tile, with two of the sides of the quadrilateral horizontal and the two remaining sides substantially parallel to a diagonal aisle, with the center of mass of the tile in the rear of the line of contact of the front face of the tile with the two tubes on which it is supported, said tile being constructed and arranged so that, on being turned from its normal position on the line of contact of its front face with the two tubes on which it is supported, all parts of the tile recesses will move away from the parts of the tubes with which they are in contact when in normal position.

5. In an inclined cross baffle for water-tube boilers having horizontally inclined tubes arranged to form horizontal and diagonal aisles, a pair of contacting walls, each composed of tiles placed edge to edge, each tile being substantially quadrilateral in elevation and having a recess at each angle of the quadrilateral arranged to fit around a tube, with two of the sides of the quadrilateral horizontal and the two remaining sides substantially parallel to a diagonal aisle, the tiles in the two walls being arranged so that no joint between the tiles of one wall is opposite a joint between the tiles of the other walls.

6. In an inclined cross baffle for water-tube boilers having horizontally inclined tubes arranged to form horizontal and diagonal aisles, a pair of contacting walls, each composed of tiles placed edge to edge, each tile being substantially quadrilateral in elevation and having a recess at each angle of the quadrilateral arranged to fit around a

tube, with two of the sides of the quadrilateral horizontal and the two remaining sides substantially parallel to a diagonal aisle, the long diagonals of all of the tiles in one wall extending in the same general direction and at an angle to the diagonals of the tiles in the other walls.

7. In an inclined cross baffle for water-tube boilers having horizontally inclined tubes arranged to form horizontal and diagonal aisles, a pair of contacting walls, each composed of tiles placed edge to edge, each tile being substantially quadrilateral in elevation and having a recess at each angle of the quadrilateral arranged to fit around a tube, with two of the sides of the quadrilateral horizontal and the two remaining sides substantially parallel to a diagonal aisle, the long diagonals of the tiles in one wall extending in the same general direction and at an angle to the diagonals of the tiles in the other wall, and the top horizontal edge of each tile in one wall being higher than the top horizontal edge of the corresponding tile in the other wall.

8. In an inclined cross baffle for water-tube boilers having horizontally inclined tubes arranged to form horizontal and diagonal aisles, a backing plate comprising a plurality of sections, each extending across and filling at least a part of a horizontal aisle between adjacent rows of tubes, with tube recesses at the top and the bottom of each section and the sections being placed edge to edge, and backing bars located in the diagonal aisles and attached to the tubes and contacting with the rear of the backing plate, each section of the backing plate contacting with at least one bar.

9. In an inclined cross baffle for water-tube boilers having horizontally inclined tubes arranged to form horizontal and diagonal aisles, a backing plate comprising a plurality of sections, each extending across and filling at least a part of a horizontal aisle between adjacent rows of tubes, with tube recesses at the top and the bottom of each section and the sections being placed edge to edge, and backing bars located in the diagonal aisles and attached to the tubes and contacting with the rear of the backing plate, each section of the backing plate contacting with at least one bar, one of the horizontal edges of each section having a portion overlapping the horizontal edge of the adjacent section.

10. In a cross baffle for water-tube boilers having horizontally inclined tubes arranged in horizontal rows, an inclined backing plate extending across the tubes and comprising a plurality of sections placed edge to edge, each section having tube recesses at the top and at the bottom and extending across and filling at least a portion of a horizontal aisle between adjacent rows of tubes, the

- sections at one edge of the plate being anchored to prevent such sections rotating on the tubes on which they rest, and other sections resting on the tubes and unattached to the tubes or the sides of the setting with their edges interlocked with the edges of adjacent sections, whereby each said other sections is prevented from rotating on the tubes on which it rests.
11. In an inclined cross baffle for water-tube boilers having horizontally inclined tubes arranged to form horizontal and diagonal aisles, a backing plate extending across the tubes and a wall of tiles in front of the plate and in contact therewith, each tile being substantially quadrilateral in elevation and having a recess at each angle of the quadrilateral arranged to fit around a tube, with two of the sides of the quadrilateral horizontal and the two remaining sides substantially parallel to a diagonal aisle, each tile having a part below the line of contact between the front face thereof and the tubes on which it rests, whereby the turning of the tile on said line of contact is prevented by the backing plate.
12. In an inclined cross baffle for water-tube boilers having horizontally inclined tubes arranged to form horizontal and diagonal aisles, a backing plate extending across the tubes, and a pair of walls of tile in front of the plate, with the rearmost wall in contact with the plate and the front wall in contact with the rear wall, each wall comprising tiles, each substantially quadrilateral in elevation and having a recess at each angle of the quadrilateral arranged to fit around a tube, with two of the sides of the quadrilateral horizontal and the two remaining sides substantially parallel to a diagonal aisle, each tile having a part below the line of contact between the front face thereof and the tubes on which it rests, whereby the turning of the tile on said line of contact is prevented by the backing plate or the wall with which the tile contacts.
13. In a water-tube boiler having horizontally inclined tubes divided into two banks, with a space between the banks, a cross baffle extending across the tubes of the upper bank and the space between the

banks, and means to support from the tubes of the upper bank, the weight of the portion of the baffle extending across said space.

14. In a water-tube boiler having horizontally inclined tubes divided into two banks, with a space between the banks, a cross baffle extending across the tubes of the upper bank and the space between the bank, said baffle comprising a backing plate and one or more walls of tile, said backing plate having a section extending across said space and supported on the tubes of the upper banks and the tiles in the portion of the walls extending across said space being supported by said section.

15. In a water-tube boiler having horizontally inclined tubes divided into two banks, with a space between the banks, a cross baffle extending across the tubes of the upper bank and the space between the banks, said baffle comprising a backing plate and one or more walls of tile, said backing plate having a section extending across said space and supported on the tubes of the upper bank and provided with projections similar in diameter and arrangement to the tubes of the upper bank, and the tiles in the portion of the walls extending across said space being similar in shape and size to the tiles forming the remainder of said walls and supported on said projections.

16. In a water-tube boiler having horizontally inclined tubes divided into two banks, with a space between the banks, a cross baffle extending across the tubes of the upper bank and the space between the banks, said baffle comprising a backing plate and one or more walls of tile, said backing plate having a section extending across said space and provided with projections similar in diameter and arrangement to the tubes of the upper bank, and the tiles in the portion of the walls extending across said space being similar in shape and size to the tiles forming the remainder of said walls and supported on said projections

JOHN PRENTICE.
